(57) ABSTRACT

An antenna structure includes a metal member, an extending section, and a metal sheet. The metal member defines a gap. The gap divides the metal member into a first portion and a second portion. The extending section is connected to the first portion of the metal member to cooperatively form a first antenna. The first antenna, the metal sheet and the second portion of the metal member cooperatively form a second antenna.

1

ANTENNA STRUCTURE AND WIRELESS
COMMUNICATION DEVICE

BACKGROUND

1. Technical Field

The disclosure generally relates to antenna structures and wireless communication devices, and particularly to an antenna structure formed by a metal shell of a wireless communication device.

2. Description of Related Art

Metal shells are widely used in wireless communication devices because of the advantages of mechanical strength, resistance to deformation, and tactile sensation. However, the metal shells may shield and interfere with signals radiated by antennas of the wireless communications and negatively influences a radiation efficiency of the antennas.

Therefore, there is room for improvement within the art.

BRIEF DESCRIPTION OF THE DRAWING

Many aspects of the present disclosure can be better understood with reference to the following drawing. The components in the drawing are not necessarily drawn to scale, the emphasis instead being placed upon clearly illustrating the principles of the disclosure.

The FIGURE is a schematic view of a wireless communication device having an antenna structure, according to an exemplary embodiment of the disclosure.

DETAILED DESCRIPTION

The FIGURE is a schematic view of a wireless communication device **300** having an antenna structure **100**, according to an exemplary embodiment of the disclosure. The wireless communication device **300** may be as a mobile phone, or a personal digital assistant, for example, and further includes a circuit board **200** (schematically shown). The circuit board **200** includes a feed point **210** and a ground point **230**. The feed point **210** is configured to feed current for the antenna structure **100**. The ground point **230** is configured to provide ground for the antenna structure **100**.

The antenna structure **100** includes a metal member **10** (partially shown), an extending section **30**, and a metal sheet **50**.

The metal member **10** is an appearance element of the wireless communication device, such as a metal frame. In this embodiment, the metal member **10** is a frame structure, which includes, in part: a first frame leg **12**, a second frame leg **14**, and a third frame leg **16**. The second frame leg **14** and the third frame leg **16** are respectively connected to two ends of the first frame leg **12**. A gap **122** is defined in the first frame leg **12** adjacent to the second frame leg **14** dividing the first frame leg **12** to form a first panel portion **124** and a second panel portion **126** spaced from the first panel portion **124**. The first panel portion **124** is connected to the second frame leg **14** to form a first portion of the metal member **10**. The second frame leg **14** is secured to the circuit board **200** by a conventional mechanical securing way such as screwing and is electronically connected to the ground point **230** by a first screw (not shown). The first panel portion **124** includes a first connecting contact **D**. The connecting contact **D** is electronically connected to the feed point **210** by a connecting member **150** (e.g. a feed line, a probe, an elastic sheet). The extending section **30** is secured to an end of the first panel portion **124** by the conventional mechanical securing way such as soldering (not shown) and also parallel

2

to the second frame leg **14**. The first combing portion **124**, the second metal frame **14**, and the extending section **30** cooperatively form a first antenna operating at a first working mode to receive a first frequency band signal (e.g. a WiFi signal).

The second combing portion **126** is connected to the third frame leg **16** to form a second portion of the metal member **10**. The third frame leg **16** is secured to the circuit board **200** by the conventional mechanical securing way such as screwing and also electronically connected to the ground point **230** by a second screw (not shown). The metal sheet **50** includes a second connecting contact **E**. The second connecting contact **E** is electronically connected to the ground point **230** by the connecting member **160** (e.g. a feed line, a probe, an elastic sheet). The metal sheet **50** can be positioned at a housing of the wireless communication device. In this embodiment, the metal sheet **50** is a rectangular sheet including two opposite first edges **51** and two opposite second edges **53** shorter than the first edges **51**. One of the first edges **51** faces to the gap **122** and is opposite to and parallel with the first frame leg **12**. One of the second edges **53** is parallel to and spaced from the extending section **30**. Thus, the first frame leg **12**, the extending section **30** and the metal sheet **50** generate a coupling and resonance effect so that the first antenna, the second panel portion **126**, the third frame leg **16**, and the metal **50** cooperatively serve as a second antenna. The second antenna operates a second working mode to receive and transmit a second frequency band signal (e.g. a GPS signal).

In use, the current is fed into the first connecting point **D** from the feed point **210** by the connecting member **150**. A first portion of the current flows through the extending section **30**. A second portion of the current flows through the second frame leg **14**. The first portion and the second portion of the current finally flow into the ground point **230** by the ground point **230** to form a first antenna path.

On another aspect, a third portion of the current flowing to a distal end of the first panel portion **124** also is coupled to the second panel portion **126** and finally flows into the ground point **230** via the third frame leg **16**. Meanwhile, the current flowing through the extending section **30** also is coupled to the metal sheet **50**, and then flows through the second panel portion **126** and finally flows into the ground point **230** via the third frame leg **16**. In addition, current fed into the metal sheet **50** from the circuit board **200** also is coupled to the second panel portion **126** and finally flows into the ground point **230** via the third frame leg **16**. Thus, the first panel portion **124**, the metal sheet **50**, the second panel portion **126**, and the third frame leg **16** cooperatively form a second antenna path.

The antenna structure **100** divides the metal member **10** into the first portion and the second portion by the gap **122** defined in the metal member **10** so that bandwidths of the first antenna and the second antenna can be adjusted by changing a position of the gap **122**. For example, when the position of the gap **122** is adjacent to the third metal frame **16**, a length of the first antenna path is lengthened so that a central frequency of the first frequency band becomes low. Meanwhile, a length of the second antenna path is shortened so that a central frequency of the second frequency band becomes high. Thus, the frequency band of the antenna structure **100** can be flexibly changed.

The metal member **10**, the extending section **30**, and the metal sheet **50** are spaced from each other. Meanwhile, the wireless communication device **300** integrates the metal member **10** as a portion of the antenna structure **100** to avoid

3

the metal member **10** from negatively influencing radiation efficiency of the antenna structure **100**.

It is believed that the exemplary embodiments and their advantages will be understood from the foregoing description, and it will be apparent that various changes may be made thereto without departing from the spirit and scope of the disclosure or sacrificing all of its material advantages, the examples hereinbefore described merely being preferred or exemplary embodiments of the disclosure.

What is claimed is:

1. An antenna structure, comprising:
a metal member being a frame structure and comprising
a first frame leg, a second frame leg and a third frame
leg, the first frame leg comprising two ends, wherein
the second frame leg perpendicularly connects to one
end of the first frame leg and the third frame leg
perpendicularly connects to the other end of the first
frame leg, and wherein the first frame leg defines a gap,
the gap divides the first frame leg into a first panel
portion and a second panel portion, spaced apart from
the first panel portion, the first panel portion connects
to the second frame leg to form a first portion, and the
second panel portion connects to the third frame leg to
form a second portion;
an extending section perpendicularly connected to one
side of the first panel portion where the second frame
leg is positioned, the extending section being parallel to
the second frame leg, wherein the first panel portion,
the second frame leg, and the extending section
together form a first antenna; and
a metal sheet, wherein the first antenna, the metal sheet,
and the second portion of the metal member together
form a second antenna.

2. The antenna structure of claim 1, wherein the metal
sheet comprises two opposite first edges and two opposite
second edges, one of the first edges faces the gap, one of the
second edges is parallel to and spaced apart from the
extending section, the extending section and the metal sheet
generate a coupling and resonance effect.

3. The antenna structure of claim 1, wherein the first panel
portion comprises a first connecting point adjacent to an end
of the second frame leg to feed current to the antenna
structure, wherein when the current is fed into the first
connecting point, a first portion of the current flows through
the extending section, and a second portion of the current
flows through the second frame leg, wherein the extending
section and the second frame leg together form a first
antenna path.

4. The antenna structure of claim 3, wherein a third
portion of the current flowing to a distal end of the first panel
portion flows through the second panel portion and finally
flows into the ground point through the third frame leg; the
current flowing through the extending section flows through
the metal sheet, and then flows through the second panel
portion, and finally flows into the ground point through the
third frame leg; wherein the current fed into the metal sheet
from the circuit board also flows through the second panel
portion and finally flows into the ground point through the
third frame leg; and wherein the first panel portion, the metal
sheet, the second panel portion, and the third frame leg
together form a second antenna path.

4

5. A wireless communication device, comprising:
a circuit board, the circuit board comprising a feed point and a ground point;
an antenna structure connected to the feed point and the ground point, the antenna structure comprising:
a metal member, the metal member being a frame structure and comprising a first frame leg, a second frame leg and a third frame leg, the first frame leg comprises two ends, wherein the second frame leg perpendicularly connects to one end of the first frame leg and the third frame leg perpendicularly connects to the other end of the first frame leg, and wherein the first frame leg defines a gap, the gap divides the first frame leg into a first panel portion and a second panel portion, spaced apart from the first panel portion, the first panel portion connects to the second frame leg to form a first portion, and the second panel portion connects to the third frame leg to form a second portion;
an extending section, the extending section perpendicularly connected to one side of the first panel portion where the second frame leg is positioned, the extending section being parallel to the second frame leg, wherein the first panel portion, the second frame leg, and the extending section together form a first antenna; and
a metal sheet, wherein the first antenna, the metal sheet, and the second portion of the metal member together form a second antenna.

6. The wireless communication device of claim 5, wherein the second frame leg and the third frame leg are electronically connected to the ground point, the metal sheet comprises two opposite first edges and two opposite second edges, one of the first edges faces the gap, one of the second edges is parallel to and spaced apart from the extending section, the extending section and the metal sheet generate coupling and resonance effect.

7. The wireless communication device of claim 5, wherein the first panel portion comprises a first connecting point adjacent to an end of the second frame leg connected to the feed point, wherein when the current is fed into the first connecting point, a first portion of the current flows through the extending section and a second portion of the current flows through the second frame leg, wherein the extending section and the second frame leg together form a first antenna path.

8. The wireless communication device of claim 7, wherein a third portion of the current flowing to a distal end of the first panel portion flows through the second panel portion and finally flows into the ground point through the third frame leg; wherein the current flowing through the extending section flows through the metal sheet, and then flows through the second panel portion and finally flows into the ground point through the third frame leg; current fed into the metal sheet from the circuit board also flows through the second panel portion and finally flows into the ground point through the third frame leg; and wherein the first panel portion, the metal sheet, the second panel portion, and the third frame leg together form a second antenna path.
